THREAD ROLLING APPARATUS

William Stern, Park Ridge, Ill., assignor to Illinois
Tool Works, Chicago, Ill., a corporation of Illi-
nois

Application January 25, 1951, Serial No. 207,673

13 Claims. (Cl. 80—8)

1

This invention relates generally to apparatus for forming threads on fastener elements and specifically to a machine for rolling threads on screw blanks.

The principal object of this invention is to provide a thread rolling machine having a greater capacity, in respect to the number of screw elements threaded per minute, than any machine heretofore known.

The standard machine for rolling threads on screw blanks employs a reciprocating die which on movement in one direction past a fixed die, in cooperation with the fixed die, rolls a thread on a screw blank inserted between the dies. In the forming of the threads, the screw is rotated in the dies through a plurality of revolutions so that the thread formed is continuous from end to end and is free of burrs and other imperfections. The standard machine produces good threads, is inexpensive, and employs standard parts, but is not entirely satisfactory because of its inherently limited capacity, the heavy parts necessary to withstand the shock of reciprocation, and the incessant vibration.

It has been proposed heretofore to employ a continuously rotating circular die cooperable with one or more arcuate dies to overcome the disadvantages of the standard machine. Such thread rolling machines have possessed various shortcomings which have prevented them from coming into commercial usage. These machines have used nonstandard dies, registration of the fixed and moving dies has been difficult to obtain, circular dies have been extremely costly, machines designed to roll screw elements through a plurality of revolutions between circular dies have produced unsatisfactory threads, and satisfactory convergence of the dies transversely of the dies and in their direction of travel to roll threads on tapered shanks or relatively pointed screws and progressively to work or swage the screw threads has not been obtained.

An object of this invention is to eliminate the disadvantages of standard thread rolling machines and of continuously operating thread rolling machines employing circular dies while possessing the advantages of both.

Another object of this invention is to provide a continuously operating thread rolling machine using conventional flat faced or plane dies.

A further object of this invention is to provide a thread rolling machine simultaneously rolling threads on a plurality of blanks.

Another object of this invention is to provide, in a thread rolling machine, flexible means for

2

carrying a plurality of movable dies and means for firmly supporting the dies against lateral or transverse movement during the working time of the dies.

5 Another object of this invention is to provide a continuously operating thread rolling machine wherein the thread rolling mechanism is designed to receive screw elements directly from a screw feeding chute.

10 A more specific object of this invention is to provide a thread rolling machine wherein the thread rolling dies receive and support screw elements in the same inclined position in which they are fed through an inclined screw feeding chute.

15 Another object of this invention is to provide, in a thread rolling machine having a plurality of movable dies successively cooperable with a fixed die, a control member actuated in timed relation with each movable die to control the movement of screw elements from a screw feeding chute into the space between the fixed and movable dies.

20 25 Another object of this invention is to provide, in a thread rolling machine having a feed chute a combination gate and starter member, and a plurality of fixed and movable dies, means operable in accordance with the movable dies to retract the member slowly at first; then to retract the member rapidly to release a screw element and to hold the member retracted while the screw element is moved by gravity from the chute to a movable die; to advance the member rapidly thereafter and forwardly relative to the movable die to shift the screw element into registration with a fixed die; and to advance the member slowly thereafter to insure rolling of the element between the dies.

30 35 Other and further objects and advantages of the present invention will be apparent from the following description when taken in connection with the accompanying drawings wherein:

Fig. 1 is an end view of a thread rolling machine embodying the principles of my invention;

Fig. 2 is a plan view of the thread rolling machine;

Fig. 3 is a cross sectional view taken along the line 3—3 of Fig. 2;

Fig. 4 is a detailed top view showing the cooperation of the fixed and movable dies and screw element supplying mechanism;

Fig. 5 is a side view of one of the movable die blocks;

Fig. 6 is an exploded perspective view of the cam mechanism carried by a movable die block;

Fig. 7 is a perspective view showing the screw element supplying mechanism and starter as cooperating with a movable die member;

Fig. 8 is a sectional view showing the mechanism for actuating the screw element starter;

Fig. 9 is a detail view partially in section showing the adjustment for the starter mechanism; and

Figs. 10-14 are somewhat schematic top views showing the operation of the starter mechanism.

A thread rolling machine embodying the principles of my invention is shown generally in Figs. 1 and 2. The machine includes a stand or base 20 on which is mounted a plurality of brackets 22 having platforms 24. A screw feeding hopper 26 is suitably supported on each of the bracket platforms 24. As will be apparent after studying this disclosure, there may be practically any number of hoppers and supporting brackets. I have illustrated four such hoppers and brackets for purposes of explanation.

The hoppers 26 are identical and each is of the type having a scoop or funnel-like structure 28 for receiving a heterogeneous mass of screw elements. Further structure includes a rotatable drum 30 which feeds screw elements in succession into a screw feeding chute 32. Each screw feeding chute includes a pair of spaced apart rails for supporting the screw elements by the heads with their shanks depending between the rails. An overhead rail 34 is supported by one or more brackets 36 directly above the space between rails of the chute 32 to prevent screws from popping out of the chute. Suitable mechanisms including clearance wheels 38 are carried within housings 40 and driven by motors 42 to prevent screws not properly positioned in the chutes 32 from being fed down the rails toward the thread rollings dies. A vibrator device (not shown) may be attached to the rails to vibrate the rails and thus assure proper feeding of screw elements down the chutes.

The stand or pedestal 20 further supports a base plate 44 having an upstanding central back-up portion 46 (Fig. 3). The ends of the upstanding central portion 46 are arcuately relieved as at 48 (Fig. 2) to provide clearance for a pair of sprocket wheels 50 and 52. The sprocket wheel 50 is secured to a shaft 54 for rotation therewith and is spaced above the plate 44 by means of a hub 56. The shaft extends through the plate 44 and stand or pedestal 20 and has a worm wheel 58 fixed on its lower end and within a housing 60. A worm is in driving engagement with the worm wheel 58 and is keyed to a shaft 62 extending out of the housing and having a sprocket wheel 64 thereon. The sprocket wheel 64, and hence the sprocket wheel 50, is driven by a sprocket chain 66 engaged with a sprocket wheel 68 of the drive shaft of an electric motor 70.

The sprocket wheel 52 is rotatably mounted on a stub shaft 72 which is mounted in an elongated slot 73 (Fig. 2), to be adjustable toward and away from the sprocket wheel 50. An endless conveyor 74 including a sprocket chain 76 is passed about the sprocket wheels 50 and 52. For utmost traction and stability the sprocket chain 76 preferably is of considerable height. Such height is readily achieved by utilizing a pair of common sprocket chains stacked one on top of the other and secured together by long screws or pins 78 passing through some of the pivotal points of the links of the chains.

A plurality of die blocks 80 is secured on the

endless chain 76 by means of the long screws 78. The rear faces of the blocks are recessed at 82 to receive the chain 76 and the screws 78 fit through countersunk apertures 84 in the rear surfaces of the blocks and are threaded into the blocks above the recesses 82. A retainer plate 86 is secured on top of the back-up block 46 by means of bolts 88 and the longitudinal edges of this plate fit within shoulder portions 90 at the upper inner edges of the blocks 80. The plate 86 extends substantially from the sprocket wheel shaft 54 to the sprocket wheel shaft 72 and maintains the lower flat face 92 of each block in firm sliding contact with the upper surface of the base 44 while the blocks move along the straight reaches of the conveyor. A portion of the lower face of each block 80 is arranged at an acute angle relative to the horizontal as at 94. Elongated runner strips 96 which are wedge shaped in cross section are arranged longitudinally of the conveyor reaches and underlie the inclined bottom face portions 94. The runner strips are secured in place by screws 98 fitting through countersunk apertures 100 in the base or support 44 and threaded into the runner strips 96. The runner strips hold the blocks 80 in firm engagement with the back up block 46 and the retainer plate 86 to prevent lateral and vertical shifting of the blocks while moving along the reaches of the conveyor.

The upper faces 102 are substantially parallel to the inclined lower face portions 94 and upper portions 104 of the blocks are inclined so as to be substantially perpendicular to the top faces. Each outer upper inclined face 104 is provided with a recessed portion 106 and a die 108 having a thread rolling surface 110 is secured therein by a clamp member 112. The clamp member is substantially in the form of a bridge having depending longitudinal flanges impinging respectively against the top of the die 108 and the upper face 102 of the block 80. The clamping member 112 is secured in clamping position by a bolt or screw 114 extending through the bridge member and threaded into the upper face of the die block 80. As may be seen in Fig. 5, the dies 108 are shorter than the recesses 106. Set screws 116 are threaded into the die blocks 80 from the ends thereof and abut the dies to provide for longitudinal positioning thereof and further to secure the dies within the recesses.

A bracket 118 extends upwardly from the support or pedestal 20 substantially beneath each screw feed chute 32. Each such bracket is provided at its upper end with a recessed portion 120. A stationary die block 122 is carried within each recessed portion 120 and includes a front face 124 substantially parallel to the thread rolling faces 110 of the dies 108. Each die block 122 carries a die 126 having a thread rolling surface 128 in opposed face to face spaced relation with the movable dies 108. Each die block 122 is provided with an arm 130 extending outwardly from the face 124 and positioning the die 126 against the adjacent feed chute 32, a shim 132 being provided between the arm and die for this purpose. Bridge-like clamps 134 similar to the clamps 112 secure the dies in place in the die blocks under the clamping influence of screws 136. In order to provide for adjustment of the movable dies 126 relative to the fixed dies 108, and thus to insure proper registration of the movable and fixed dies, the die blocks 122 are adjustably secured on the brackets 118.

The adjustable mounting of the die blocks,

as seen in Figs. 1-4 includes a pair of screws 138 extending downwardly through transversely elongated slots 140 in the die blocks. A pair of take-up screws 142 extends through each bracket from the rear thereof and is threaded into the die block 122 substantially on a central plane thereof to pull die block toward the bracket. Set screws 144 on either side of the take-up screws 142 are threaded through the bracket and abut the rear face of the die block 122. Loosening of the clamping screws 138 and adjustment of the take-up screws 142 and set screws 144 allows adjustment of each die block 122 to bring the thread rolling surfaces 128 of the dies 126 into proper spaced relation with the thread rolling surfaces 110 of the movable dies 108. Subsequent tightening of the clamping screws 138 aids in maintaining the die blocks 122 in proper adjusted position.

Proper insertion of a screw blank between movable and fixed dies for rolling threads on the screw blanks as the dies come into opposed face to face relation is brought about by starter mechanisms illustrated in Figs. 5-9. Adjacent each screw feed chute 32 on the leading or upstream side thereof (the side from which the confronting reach of movable die blocks is approaching) there is positioned a bracket 146 upstanding from the pedestal or support 20. A forked lever 147 is pivoted on a screw or pin 148 and spaced from the front wall of the bracket 146 by a hub 150. One arm 152 of the lever 147 extends substantially straight down from the pivot 148 and is biased in a clockwise direction as seen in Fig. 7 by a tension spring 154 connected between the extremity of the arm 152 and a fixed point 155 on the support 20. A second arm 156 of the lever extends at an acute angle relative to the arm 152 from the pivot point 148. The extremity of the arm 156 is provided with a cam follower roller 158 supported on the end of a screw 160 and spaced from the arm 156 by a tubular sleeve 162.

The bracket 146 is provided near its upper end with a bracket or support 164 having a back plate 166 secured against the front face of the bracket 146 and a pair of arms 168 extending forwardly therefrom. The arms 168 support a slide block 170 which may be secured to the arms by means such as screws 172. The slide block 170 is provided with a longitudinally extended dovetail slot or groove within which slidably rides a dovetail slide 174. A block 176 is secured to the slide 174 or is integral therewith and has a front face 178 parallel to the front face of the adjacent fixed die 126 and substantially in the plane thereof. A gate member 180 is secured to the front face 178 of the block 176 by screws 181 fitting through countersunk bores in the block and threaded into the gate member. The gate member 180 consists of an elongated plate slightly thinner than the space between opposed fixed and movable dies and extending beyond the slide and block 174 and 176.

A pin 182 extends rearwardly from the slide 174 through a longitudinally elongated slot 184 in the slide block 170. A third arm 186 of the lever 147 extends substantially vertically upwardly from the pivot 148 and is provided with a slot 188 at its upper end. The pin 182 is received in the slot 188 to cause the slide 174 to be moved by the lever 147.

Movement of the lever in a clockwise direction, and hence of the slide 174 in a down stream direction, is limited by a stop member 190 shown in Fig. 9. The stop member includes a plate 75

192 provided with a rearwardly extending arm 194 fitting within a slot in one of the arms 168 and pivoted on a pin 196. A set screw 198 is threaded through the arm 168 and abuts the upper end of the plate 192 to limit movement thereof. A jam nut 200 locks the set screw in place. A curled tail 202 on the lower end of the plate 192 engages the under side of the arm 198 to limit movement of the plate 192 in a counterclockwise direction.

Each of the movable die blocks 88 carries camming mechanism 204 as shown in Figs. 3, 5, 6 and 8. Each of the camming mechanisms 204 includes a plate 206 secured adjacent the bottom of the vertical portion of the outer or rear block face by means of a screw 208 and dowel pins fitting through apertures 210 in the extremities of the plate 206 and into cooperating bores in the blocks 88. An angle member 212 is secured to the plate 206 by screws 214 fitting through vertically elongated slots 216 in the vertical flange of the angle member and threaded into the plate 206. A vertically elongated slot 218 in this flange accommodates the head of the screw 208. A cam 220 is supported on the horizontal flange of the angle member 212 by means of screws 222 fitting through longitudinally elongated slots 224 in the horizontal flange and threaded into the cam. The cam is longitudinally symmetrical and is provided with a central raised flat or dwell 226. The cam drops off abruptly from each end of the flat portion 226 as at 228 and then tapers at a relatively flat angle as at 231 to the extremities of the cam. The cam mechanisms 204 are adapted to engage the cam follower rollers 158 to deliver screw blanks to the spaces between opposed movable and fixed dies as will be apparent from the ensuing paragraphs.

Each of the plurality of stationary dies and screw supplying mechanisms associated therewith is identical and an explanation of the operation of a single one of them therefore will suffice. The operation best is understood with reference to the somewhat schematic sequence diagrams of Figs. 10-14. Screw blanks 230 in a screw feed chute 32 normally are retained therein by the gate member 180 which extends across the lower end of the feed chute. In the position of the parts shown in Fig. 10, the gate member 180 is at its extreme rightmost position under the influence of the tension spring 154, the cam follower roller 158 not being contacted by any cam at this time. Certain of the parts and also the screw elements are designated in the sequence views of Figs. 10-14 by the numerals heretofore used with the addition of subscripts to aid in following the individual elements and parts.

In Fig. 10 a screw element 230a is shown being rolled between a stationary die 126 and a movable die 108a passing in closely spaced opposed face to face relation thereto. In Fig. 11 the succeeding movable die 108b has advanced toward the fixed die 126 and one of the shallow cam faces 231 of the cam 220 carried by the movable die block carrying the die 108b has encountered the cam follower roller 158. This causes the gate member 180 to be retracted to the position shown in Fig. 11 at which time a steep cam surface 228 engages the cam follower roller 158 to pivot the lever 147 a greater distance counterclockwise to retract the gate member 180 to its fullest extent. Fig. 12 shows the gate member fully retracted as the cam follower roller rides on top of the dwell portion 226 of the cam.

In its fully retracted position, the gate mem-

ber 180 allows the next screw element 230b to fall from the end of the chute against the movable die 108b. As the cam follower roller moves along the succeeding steep portion 228 of the cam, the spring 154 pivots the lever 147 clockwise to shift the gate member to the right, as shown in Fig. 13, at a more rapid rate than the movement of the movable die. As the gate member moves to the right, it pushes the screw element 230b ahead of it into the space between the stationary die 126 and movable die 108b as they move into opposed position.

Movement of the screw element 230b into the space between the dies under the impetus of gate member 180 is illustrated in Figs. 13 and 14. When the screw element shank first is engaged by the screw working or thread rolling surfaces of the dies the gate member 180 continues at a decreased rate to push the screw element before it and thus to insure the proper starting of rotation of the screw element between the dies. When the cam follower roller 158 leaves the cam, the gate member 180 reaches the position shown in Fig. 10 and is ready to perform another control operation when engaged by the succeeding cam.

When no longer acted upon by the gate member 180, screw elements are rolled through a plurality of revolutions by the dies to form threads thereon and then fall from the trailing ends of the fixed dies 126 and die blocks 122 into the enlarged open upper ends 232 of chutes 234 extending beneath the machine to deliver threaded screw elements to a receptacle or other apparatus (not shown). The threaded screw elements generally will fall from the dies into the enlarged chute ends 232 with no difficulty, but I prefer to provide air jets 236 positively to preclude any possibility of screw elements being carried beyond the upper chute ends 232 and to the next thread rolling station where they could cause damage to the mechanism.

It is apparent that a machine has been disclosed herein having a much higher capacity than those heretofore known. The capacity is increased by passing thread rolling dies past one another in opposed face to face relation in only one direction. The relative one way movement allows higher average operating speeds with lower maximum speeds than is possible with the reciprocating thread rolling machines known heretofore. The capacity further is increased by rolling a screw element between opposed dies each time they pass one another rather than only once for each two passings in the known reciprocating thread rolling machines. The capacity of the machine disclosed herein still further is increased by the use of a plurality of rolling stations and a plurality of sources of screw elements each of which supplies one of the thread rolling stations.

The specific embodiment of my invention shown and described is for illustrative purposes only. Various changes can be made in the details of construction without departing from the invention as expressed in the following claims.

I claim:

1. A thread rolling machine comprising a movable die unit having a planar thread rolling surface, means for moving said die unit in only one direction over a predetermined closed polygonal path, said path including a rectilinear portion, means along said rectilinear portion of said path for engaging said movable die unit to prevent displacement of said movable die unit transversely

of said rectilinear portion of said path, a stationary die unit having a planar thread rolling surface secured adjacent the rectilinear portion of said predetermined path whereby said thread rolling surfaces relatively pass one another periodically in opposed face to face spaced relation, and means for delivering screw elements to the space between said thread rolling surfaces in timed relation with the movement of said movable die unit.

2. A thread rolling machine comprising a first die unit having a planar thread rolling surface, means for moving said first die unit in only one direction over a predetermined closed polygonal path, said path including a rectilinear portion, means along said rectilinear portion of said path for engaging said first die unit to prevent displacement of said first die unit transversely of said rectilinear portion of said path, a second die unit having a planar thread rolling surface adjacent the rectilinear portion of said predetermined path whereby said thread rolling surfaces relatively pass one another periodically in opposed face to face spaced relation, said surfaces being of sufficient extent longitudinally of said path to roll a screw element through a plurality of revolutions, and means for delivering screw elements to the space between said thread rolling surfaces in timed relation with the relative movement of said die units.

3. A thread rolling machine comprising a movable die unit having a thread rolling surface, means for moving said movable die unit in only one direction over a predetermined closed path having straight and curved portions, means along a straight portion for restraining said die unit from movement transversely of said path, a stationary die unit having a thread rolling surface secured adjacent said straight portion of said path whereby said thread rolling surfaces relatively pass one another periodically in substantially parallel opposed face to face spaced relation, means for adjusting the spacing between said thread rolling surfaces, and means for delivering screw elements to the space between said thread rolling surfaces in timed relation with the movement of said movable die unit.

4. A thread rolling machine comprising a movable die unit having a thread rolling surface disposed at an acute angle to the horizontal, means for moving said movable die unit in only one direction over a predetermined closed polygonal path, a stationary die unit having a thread rolling surface disposed substantially parallel to said movable thread rolling surface and secured adjacent said predetermined path whereby said thread rolling surfaces relatively pass one another in succession in the same direction and in opposed face to face substantially uniformly spaced relation, a screw element feeding chute, and means for delivering screw elements inclined at the same angle as said thread rolling surfaces directly from said chute to the space between opposed thread rolling surfaces in timed relation with the movement of said movable die unit.

5. A thread rolling machine comprising an endless belt having two oppositely disposed rectilinear reaches, a plurality of movable die blocks carried by said belt and each having a planar screw working surface, a central block within said belt and backing up said die blocks as they move along said reaches, a plurality of stationary die blocks mounted in spaced relation to said endless belt along said reaches and each having a planar screw working surface facing said belt,

means for driving said belt at a uniform constant rate whereby the movable die block working surfaces pass said stationary die block working surfaces successively in opposed face to face spaced relation, means including said central block for supporting each movable die block against movement transversely of said belt as it passes a fixed die block, equal numbers of movable blocks on each reach passing fixed die blocks at the same time to balance out reactions on said central block, and means for introducing screw elements into the spaces between opposed working surfaces in timed relation to the movement of said endless belt.

6. A thread rolling machine comprising a fixed die unit having a screw working surface, means for feeding screw elements along a predetermined path to a terminal point adjacent said fixed die unit, a movable die unit having a screw working surface, means for moving said movable die unit past said fixed die unit with said working surfaces in opposed face to face spaced relation, a shiftable member engageable with the shanks of screw elements for controlling movement of screw elements from said terminal point to the space between said working surfaces, and means including means carried by said movable die unit for shifting said shiftable member whereby positively to force the shanks of screw elements into the space between said working surfaces in timed relation to the movement of said movable die unit.

7. A thread rolling machine comprising a fixed die unit having a planar screw element threading surface, a chute for feeding screw elements along a predetermined path to a terminal point adjacent said fixed die unit, a movable die unit having a planar screw element threading surface, means for moving said movable die unit past said fixed die unit with said threading surfaces in opposed face to face spaced relation, a reciprocable member engageable with screw element shanks and positioned across said chute at said terminal point for controlling the movement of screw elements from said terminal point to the space between said working surfaces, and means including a cam carried by said movable die unit for reciprocating said reciprocable member whereby to control the movement of screw elements from said chute and to force the shanks of the screw elements into the space between said working surfaces in timed relation to the movement of said movable die unit.

8. A thread rolling machine comprising a fixed die unit having a planar screw element thread rolling surface, a movable die unit having a planar screw element thread rolling surface, means for moving said movable die unit past said fixed die unit with said thread rolling surfaces in opposed face to face spaced relation, a screw element feed chute terminating adjacent said fixed die unit, a gate and starter member engageable with the shanks of screw elements closing the end of said feed chute and reciprocable toward and away from said fixed die unit, lever means for reciprocating said gate, and a cam carried by said movable die unit for actuating said lever to reciprocate said gate and starter member whereby to release screw elements from said feed chute and to feed them positively by the shanks into the space between said thread rolling surfaces in timed relation to the movement of said movable die unit.

9. A thread rolling machine comprising a fixed die unit having a planar screw element thread

rolling surface, means for feeding screw elements along a predetermined path to a terminal point adjacent said fixed die unit, a movable die unit having a planar screw element thread rolling surface, means for moving said movable die unit past said fixed die unit in only one direction with said working surfaces in opposed face to face relation, a shiftable combination gate and starter member normally positioned across said screw element feeding means at said terminal point engage screw element shanks to retain screw elements in said feeding means, means for shifting said gate and starter member in timed relation to the movement of said movable die unit to release a screw element from said feeding means, and means for shifting said gate and starter member in timed relation to the movement of said movable die unit to engage the released screw element and shift said released screw element into rolling engagement with said screw working surfaces, both of said shifting means including a cam having a cam surface for retracting said member to release a screw element, a dwell for allowing seating of a screw element in front of said member and a cam surface for shifting said member forwardly to engage the shank of the released screw element to force it into said rolling engagement, both of said cam surfaces being relatively abrupt adjacent said dwell and being relatively shallow away from said dwell.

10. A thread rolling machine comprising a movable die unit having a planar thread rolling surface, means for moving said die unit in only one direction over a predetermined closed polygonal path, said path including a rectilinear portion, means along said rectilinear portion of said path for engaging said movable die unit to prevent displacement of said movable die unit transversely of said rectilinear portion of said path, a stationary die unit having a planar thread rolling surface secured adjacent the rectilinear portion of said predetermined path whereby said thread rolling surfaces relatively pass one another periodically in opposed face to face relation, means for feeding screw elements along a predetermined path to a terminal point adjacent said fixed die unit, a shiftable member engageable with the shanks of screw elements for controlling movement of screw elements from said terminal point to the space between said working surfaces, and means including means carried by said movable die unit for shifting said shiftable member in timed relation with the movement of said movable die unit whereby positively to force the shanks of screw elements into the space between said thread rolling surfaces whereby to roll threads on said shanks.

11. A thread rolling machine as set forth in claim 10 wherein the means carried by the movable die unit for shifting the movable member comprises a cam.

12. A thread rolling machine comprising an endless belt having two oppositely disposed rectilinear reaches, a plurality of movable die blocks on said belt and each having a planar screw working surface, a plurality of stationary die blocks mounted in spaced relation to said endless belt along said rectilinear reaches and each having a planar screw working surface facing said belt, means for driving said belt at a uniform constant rate whereby the movable die block working surfaces pass said stationary die block working surfaces successively in opposed face to face spaced relation, means for supporting each movable die block against movement

11

transversely of said belt as it passes a fixed die block, means for feeding screw elements along a plurality of predetermined paths to a terminal point adjacent each fixed die block, a plurality of shiftable members engageable with the shanks of screw elements for controlling the movement of screw elements from said terminal points to the spaces between the working surfaces as the movable die blocks pass the fixed die blocks, and means including means carried by said movable die blocks for shifting said shiftable members whereby positively to force the shanks of screw elements into the spaces between said working surfaces in timed relation to the movement of said movable die blocks.

5 10 15

12

13. A thread rolling machine as set forth in claim 12 wherein the means carried by the movable die blocks comprise cams.

WILLIAM STERN.
